(57) CLAIM

The ornamental design for a grille for automobiles, as shown and described.

DESCRIPTION

FIG. 1 is a front elevational view of a grille for automobiles showing my new design;

FIG. 2 is a top plan view thereof;

FIG. 3 is a right side elevational view thereof, the left side elevational view being a mirror image of the right side elevational view; and,

FIG. 4 is a front perspective view thereof.

The bottom and rear views are not ornamental.

The portions shown in broken lines form no part of the claimed design.
